UNITED STATES PATENT OFFICE

CLIFFORD F. RANDOLPH, OF PLAINFIELD, NEW JERSEY, ASSIGNOR, BY MESNE ASSIGNMENTS, TO GENERAL MACHINERY CORPORATION, OF HAMILTON, OHIO, A CORPORATION OF DELAWARE

TRAVERSING MECHANISM FOR RADIAL DRILLS

Application filed November 25, 1925. Serial No. 71,362.

This invention relates to traversing means for the tool head of a radial drill along its horizontally extending arm and for traversing other members.

5 An object of the invention is to provide improved traversing mechanism for rapidly moving the tool head of a radial drill along its arm in either direction, either manually or by power applied thereto.

10 Another object of the invention is to provide a single actuating member by means of which the head may be traversed manually along the arm in either direction or power means may be engaged thereby to traverse the head in either direction.

One feature which is advantageous is that a single handle is provided which in one position may be oscillated horizontally in either direction to traverse the head along its arm, or, in another position the handle may be oscillated to engage a clutch to actuate power mechanism so that the head may be traversed in either direction by motive power on the drill.

25 Another feature of importance is that a constantly rotating screw having right and left hand threads is provided extending along the rail and engaged by individual nuts. Either one of these nuts is adapted to be clutched to a nonrotatable member on the head.

With the above and other objects in view, my invention consists in the features of construction and operation set forth in the following specification and illustrated in the accompanying drawings.

In the accompanying drawings annexed hereto and forming a part of this specification, I have shown my invention embodied in the head of a radial drill having a horizontal arm, but it will be understood that the invention can be otherwise embodied and that the drawings are not to be construed as defining or limiting the scope of the invention, 45 the claims appended to this specification being relied upon for that purpose.

In the drawings:

Figure 1 is a front elevation of a part of a radial drill arm and head having the present 50 invention applied thereto.

Fig. 2 is a side elevation of the head and arm, parts being shown in cross section.

Fig. 3 is a horizontal sectional view taken upon the line 3—3 of Fig. 2.

Fig. 4 is a cross sectional view upon an 55 enlarged scale of the power traversing means, and

Fig. 5 is an enlarged view of the operating handle and connected parts in cross section.

In the above mentioned drawings I have shown but one embodiment of the invention which is now deemed preferable, but it is to be understood that changes and modifications may be made within the scope of the appended claims without departing from the spirit 65 of the invention.

Briefly, and in its broadest aspect, my invention comprises the following principal parts: first, an arm; second, a head movably supported thereon; third, a rack extending along the arm; fourth, a pinion on the head engaging said rack; fifth, a shaft carrying said pinion; sixth, a handle adapted to be attached to the shaft so that the pinion may be 75 rotated slightly to manually traverse the head in either direction along the arm; seventh, a left and right hand threaded screw extending along the arm; eighth, nuts engaging the individual threads of said screw; ninth, a 80 clutch adapted to engage either one of said nuts; and tenth, means actuated by oscillatory movement of the handle for actuating the clutch.

Referring more in detail to the figures of 85 the drawings, the invention is adapted primarily for traversing a tool carrying head 10 on a horizontally extending arm 11 as shown in Figs. 1 and 2. Only limited portions or parts of the arm 11 and the head 10 are shown, 90 and it will be understood that the mechanism for rotating a spindle 12 in the head 10 and advancing it during its feeding operation may be of any usual type. Also, a column (not shown) of any well-known or 95 usual construction may be used for horizontally supporting the arm so that it may be raised and lowered.

Along the arm 11 extends a rack 13, preferably in a direction parallel to the move- 100

ment of the head 10. Adapted to engage this rack 13 is a pinion 14 keyed, or otherwise secured, to the upper end of a vertical shaft 15 rotatably mounted within the head 10. At the lower end of the shaft 15 is a member keyed thereto so that oscillation of the member 16 will oscillate the shaft 15 and pinion 14 in either direction to traverse the head 10 correspondingly along the arm 11.

10 To oscillate the member 16 and the shaft 15 a handle 17 is provided. This handle 17 is pivotally mounted on a sleeve 18 surrounding the shaft 15 and supported within the head 10. For this purpose the sleeve 18 is provided with a circumferential groove 19 which may be engaged by a pin 20. On the member 16 are teeth so that this member forms one-half of a clutch. The other half of the clutch member 21 having interengaging teeth is keyed to the lower end of a sleeve 22 slidable upon the shaft 15 and within the member 18. With this sleeve 22 lowered so that the teeth of the clutch members 16 and 21 are interengaged the shaft 15 may be oscillated by oscillation of the handle 17. As shown in Fig. 5 the handle 17 pivotally engages the sleeve member 18 so that vertical oscillation of the handle 17 engages and disengages the members 16 and 21 of the clutch.

20 By means of this mechanism the handle 17 when the clutch members 16 and 21 are engaged may be oscillated horizontally to slightly rotate the shaft 15 in either direction. Repeated oscillations of the handle 17 horizontally and vertically to engage and disengage the clutch 16-21 enables the pinion 14 to be rotated slightly to adjust the head 10 along the arm 11 manually.

Extending along the arm 11 in a direction parallel to the movement of the head 10 is a screw 25, preferably double threaded, with a left and right hand thread, as shown clearly in Figs. 1 and 4. Engaging this screw 25 are two nuts 26 and 27 one of which engages the left hand thread and the other the right hand thread. These nuts 26 and 27, as will be seen in Fig. 3, may be formed of babbitt or other bearing material and are positioned within sleeves 28 and 29. On the end of each sleeve 28 and 29 is one member of a cone clutch 30 and 31 respectively. By means of suitable internal projections 31^a formed on the sleeves 28 and 29 this bearing material may be held from rotating relative to its sleeve. As shown in Fig. 4, these sleeves 28 and 29 are positioned in opposed relation to each other and are spaced from each other and from parts of the head 10 by suitable thrust bearings 32, preferably of the ball type. Surrounding these sleeves 28 and 29 so that the sleeves may normally rotate within it is a clutch member 33 having at its opposite ends conical recesses adapted to interengage with the conical ends 30 and 31 of the nuts 26 and 27. This clutch member 33 is adapted to slide axially rela-

tive to the nuts 26 and 27 and sleeves 28 and 29 a limited distance so that one or the other of the sleeves 28 or 29 may be gripped by the clutch member 33. The clutch member 33 is held against rotation while being permitted to move axially by means of splines or keys 34. It will be seen from this operation that by moving the clutch member 33 in one direction one of the nuts 26 may be held against rotation so that rotation of the threaded shaft 25 will traverse the head 10 in one direction due to the rotation of the screw 25. By engaging the other nut 27 with the clutch member 33 the traversing movement of the head 10 will be in the opposite direction. Normally the screw 25 is continuously rotated and, as the lead of the threads is long, the nut 26 or 27 not engaged by the clutch 33 will be rotated and advanced along the screw 25. The clutch member 33 is suitably retained within a recessed portion of the head 10 and is slidable thereupon while being held against rotation by keys 34 freely slidable within splines formed within the head 10.

In order to actuate the clutch member 33 to engage either of the nuts 26 or 27, use is made of the handle 17 previously described for effecting the manual traversing movement. The sleeve 22 surrounding the lower portion of the vertical shaft 15 is provided at its upper end with suitable clutch teeth 22^a adapted to engage corresponding tooth portions 35^a on a yoke member 35 loosely mounted on and surrounding the vertical shaft 15. This member 35 has shoes 36 engaging an annular recess 37 within the clutch member 33. It will be seen from this construction that oscillation of this yoke member 35 will move the clutch member 33 in either direction and thus operate the power mechanism for effecting the traversing motion. In order to engage the members of this clutch, the handle 17 at the lower end of the vertical shaft 15 is first oscillated vertically to engage teeth 35^a on the yoke 35 with the teeth 22^a on sleeve 22 after which horizontal oscillation of the handle 17 will engage one or the other of the nuts 26 or 27.

From this construction it will be seen that the handle 17 when in its lower oscillated position may be used to manually traverse the head 10 along the arm 11 through the shaft 15, the pinion 14 and rack 13. In its upper oscillated position the handle 17 may be similarly oscillated in a horizontal plane to effect traversing movements of the head by means of the double threaded screw 25 and the clutch 33. As shown clearly in Fig. 5 vertical movement of the handle 17 disengages the teeth on members 16 and 21. Similarly downward movement of the handle 17 disengages the yoke 35 from the sleeve 22. It is therefore impossible for both clutches to be simultaneously engaged. Also, as shown in Fig. 5, the handle 17 is provided with an upward ex-

tending projection 37^a which at its upper end may have a pin 38 extending transversely into the sleeve 22. Horizontal oscillation of the handle 17 therefore oscillates the sleeve 22.

5 What I claim is:

1. A traversing mechanism for drills comprising in combination, an arm, a head mounted for movement therealong, a rack extending along said arm, a pinion on said head, manual means to rotate said pinion to traverse said head in either direction, a right and left threaded screw on said arm, means adapted to continuously rotate said screw, nuts separately engaging the threads of said screw, clutches engaging said nuts, and a single handle to manually rotate said pinion to traverse said head and to engage and disengage said clutches, whereby said head may be traversed manually or by power in either direction.

20 2. A traversing mechanism for drills comprising in combination, an arm, a head mounted for movement therealong, a rack extending along said arm, a pinion in said head, manual means to rotate said pinion to traverse said head in either direction, clutch means to engage said manual traversing means, a right and left threaded screw on said arm, means adapted to continuously rotate said screw, nuts separately engaging the threads of said screw, friction clutches engaging said nuts, and a handle to operate said manual means when said first mentioned clutch is in operative position and when oscillated to another position to actuate said friction clutches to effect traversing from said screw.

25 In testimony whereof, I hereto affix my signature.

CLIFFORD F. RANDOLPH.
